W. F. BLEECKER
ELECTROLYTIC TIMER
Filed April 16, 1925

FIG. 1.

FIG. 2.

FIG. 3.

FIG. 4.

INVENTOR.
W. F. Bleeker

BY
ATTORNEY.

UNITED STATES PATENT OFFICE.

WARREN F. BLEECKER, OF BOULDER, COLORADO.

ELECTROLYTIC TIMER.

Application filed April 16, 1925. Serial No. 23,611.

To all whom it may concern:

Be it known that I, WARREN F. BLEECKER, a citizen of the United States, residing at Boulder, in the county of Boulder and State 5 of Colorado, have invented certain new and useful Improvements in Electrolytic Timers, of which the following is a specification.

This invention relates to timers for electrical time-controlled devices and it is an 10 object of the invention to provide a simple, efficient, safe and reliable means to automatically time the completion of an electric circuit to its approximately full current-carrying capacity by electrolytic action.

15 A further object of the invention resides in connecting a timing means of the above described character in an electric circuit in series with a resistance whereby the electrolytic action is employed to reduce or eliminate the resistance at the expiration of a predetermined period of time and still another 20 object is to associate an electrolytic timer with the time-controlled ignition element of an electric bomb of the type used in shooting 25 oil wells.

With the above and other objects in view, the timer constructed in accordance with my 30 invention comprises, essentially, a container, an electrolyte therein, two normally spaced electrodes relatively disposed to gradually bridge the space between them by the electrical deposition of metal on one under electrolytic decomposition, and means for connecting the electrodes in an electric circuit, 35 and the bomb to which the timer is particularly applicable is characterized by the use of an electric circuit for the timed ignition of an electrical fulminate cap in a charge of high explosive, all contained in a water-tight shell adapted to be lowered into a well.

40 An embodiment of the invention has been illustrated in the accompanying drawings in the several views of which like parts are similarly designated and in which

45 Figure 1 represents a longitudinal section of a timing device constructed in accordance with the invention, drawn to an exaggerated scale;

50 Figure 2, a similar view of the device in the condition to which it is gradually brought by electrolytic action for the completion of a circuit in which it is connected;

55 Figure 3, a sectional elevation of an elec-

tric bomb for shooting oil wells, to which the invention is applied; and

55 Figure 4, a diagrammatic view of the circuit of the instrument shown in Figure 1.

Referring first to Figures 1 and 2 of the drawings, the timer 5 consists of a tubular container 6 made of glass or other non-conductive and chemically resistant material which is closed by a cap 7 of the same or similar qualities.

60 Conductive stems 8 and 9 passing through openings in the cap and the thereto opposed end of the container provide supports for two electrodes relatively disposed so that the electrical deposition of metal on one under electrolytic decomposition will gradually bridge the gap between them.

65 The anode electrode, designated by the reference character 10, is disposed at one end of the container; the cathode indicated by the numeral 12, is positioned in close proximity to the opposite end of the same, 70 and the container is provided with a suitable electrolyte as will hereinafter be more fully described.

75 In the construction shown in the drawings, the stems of the two electrodes are provided, 80 exteriorly of the container, with binding screws 13 and 14 for their connection in an electric circuit.

85 In the preferred form of the invention, the anode is of bulky form and composed of copper or other substance subject to corrosion and redeposition under electrolytic action, the cathode is comparatively small and flat-surfaced and the electrolyte with which the container is filled, consists of a solution of the salt of the anode as for example, 90 copper sulfate in case the anode is made of copper, or tin chloride if it is composed of tin.

95 In the use of the invention, the electrodes are by means of their binding screws, connected in an electric circuit in series with a resistance preferably associated with an electrical device adapted to be operated only by the approximately full strength of the 100 current produced at the source of electricity.

105 The current passing through the electrolyte causes the decomposition of the anode under electrolytic action and particles corresponding in number to those liberated, are electrically deposited on the cathode.

The gap or space between the two electrodes is thus gradually shortened until they are in actual contact or at least in short-circuiting vicinity to each other, when 5 the current flowing from the anode directly to the cathode is free to pass full strength to the resistance and reduce or eliminate the same.

It will be evident that in this manner, the 10 time of operation of a device with which the resistance is associated, is predetermined by the electrolytic action, and that the time period controlled by said action is determined by the nature, size and relative ar- 15 rangement of the co-operating parts of the electrolytic cell.

Specifically, the time required after the timer is connected in the circuit, to produce a contact between the electrodes for the direct passage of current between them, depends on the capacity of the container, the 20 original length of gap between the electrodes, the cross-sectional shape of the electrodes, the material of which the electrodes 25 are composed, the strength of the electrolyte, the position of the cathode relative to the end of the container, and other details of construction all of which are regulated so that the time-period represented by the electrolytic device may be accurately predetermined. 30

It is, therefore, possible to produce any 35 desired number of timer-units of different time periods, properly labeled or otherwise distinguished from each other so that the operator may select within a wide range of choice, a unit in accordance with the particular time at which the operation of the electrical time-controlled device is desired.

40 While it is preferable that the gap between the electrodes be bridged by the adherent deposition on the cathode of particles liberated by partial decomposition of the anode by electrolytic action, it is to be understood 45 that under different conditions, the metal deposited on the cathode may be drawn wholly from the electrolyte in which case the anode may be inert to electrolytic action.

50 In such a cell, the electrolyte would necessarily have to contain a sufficient quantity of the metallic element to be liberated by decomposition of the electrolyte and thereby bridge the space between the electrodes.

55 The application of my invention to an electric bomb of the type employed in shooting oil wells has been illustrated in Figure 3 of the drawings.

60 The bomb comprises a shell 16 of suitable size and form to be lowered into the bore of a well, a screw-cap 17 forming a watertight closure at an end thereof, an interior casing 18 loaded with a charge of high explosive 19, and enclosing a frame 20 above the charge, a battery 21 of the dry-cell type

inside the frame, and a pair of electrical ignition caps 22 disposed in a recess at the bottom of the casing and projecting into the explosive charge.

The caps are filled with an explosive substance such as fulminated mercury, and they carry at one of their ends in contact with their charges metallic resistance filaments 23 which only by the approximately full strength of the current produced in the battery, are brought to a temperature sufficient to heat the mercury to a point of decomposition and consequent explosion. 70 75

A suitable holder such as the spring-clip shown at 24 is disposed above the battery to secure the electrolytic timer and the anode 10 and the cathode 12 thereof are connected respectively to the positive pole and the negative pole of the battery by conductors 26 and 25. The resistance-filaments of the detonating caps are connected in the conductor 25 in multiple with relation to each other and in series with the timer. 80 85

In the operation of the bomb, the timer is connected in the circuit of the battery in the manner hereinbefore explained, shortly before the shell is lowered into the bore of the well, and by electrolytic action predetermines the time at which the current will heat the filaments of the caps sufficiently to cause the detonation of the charge of high explosive by the explosion of the fulminate. 90 95

The preferred form of the timer in which the anode is partially decomposed to bridge the space between the electrodes by the adherent deposition of the liberated particles on the cathode, is better adapted for use in connection with bombs or other devices of similar character than the form in which the anode is substantially inert and the electrolyte supplies the metallic element, since the use of the latter form involves the deposition of the oxygen equivalent of the deposited metal, which in an enclosed space could not be accomplished without apparently impractical provisions. 100 105 110

Having thus described my electrolytic timer and its application to an electrical time-controlled appliance, it will be apparent that its construction permits of adjustment to a degree of accuracy for predetermining the time period of reducing or eliminating a resistance in a circuit in which it is connected, difficult to attain by mechanically operated devices of similar character, and that with the parts of the timer properly arranged and connected in the circuit, failure in operation and the possibility of premature discharge are wholly eliminated. 115 120

What I claim and desire to secure by Letters Patent is:

1. An electrolytic timer comprising a container, an electrolyte, and spaced electrodes adapted to be connected in a circuit and relatively disposed to bridge the space between

- them by the adherent deposition of metal on one under electrolytic decomposition.
2. An electrolytic timer comprising a container, an electrolyte, and spaced electrodes adapted to be connected in a circuit and relatively disposed to bridge the space between them by the adherent deposition of metal on one under electrolytic decomposition of the other.
- 10 3. An electrolytic timer comprising a container, an electrolyte therein, spaced electrodes one of which contains a metallic element subject to corrosion and redeposition under electrolytic action, and means for connecting the electrodes in an electric circuit, the electrodes being disposed for co-operation to bridge the space between them by the adherent deposition on one of particles liberated under electrolytic decomposition.
- 20 4. An electrolytic timer comprising a container, an electrolyte therein, spaced electrodes one of which has sufficient corrosive metal to provide material for a bridge across the space by adherent deposition on the other of particles liberated under electrolytic action, and means for connecting the electrodes in a circuit.
- 25 5. An electrolytic timer comprising a container, and anode-electrode containing a metallic element subject to corrosion and redeposition, a cathode-electrode spaced from the other, an electrolyte composed of the salt of the anode metal, and means for connecting the electrodes in a circuit.
- 30 6. An electrolytic timer comprising a closed container, an electrolyte therein, spaced electrodes adapted for co-operation to bridge the space by electrical deposition of metal on one under electrolytic decomposition, and means externally of the container, to connect the electrodes in a circuit.
- 40 7. An electrolytic timer comprising a closed tubular container, an electrolyte therein, spaced electrodes at opposite ends of the
- 45 container, adapted for co-operation to bridge the space by electrical deposition of metal on one under electrolytic decomposition, and means externally of the container to connect the electrodes in a circuit.
- 50 8. An electrolytic timer comprising a container, an electrolyte therein, spaced electrodes adapted for co-operation to gradually bridge the space between them by the electrical deposition of material on one under electrolytic decomposition of the other, and means for connecting the electrodes in a circuit.
- 55 9. The combination with a circuit, of a resistance and an electrolytic cell connected in series therein, the electrolytic cell including two normally spaced electrodes relatively disposed to bridge the space between them by electrolytic decomposition.
- 60 10. An electric bomb comprising in combination a shell, an explosive charge, an electrical igniter for the charge, a source of electricity, and an electrolytic timer in circuit with the source and the igniter.
- 65 11. An electric bomb comprising in combination a shell, an explosive charge, a detonating cap for the charge, including an electric resistance, a source of electricity, a circuit connecting the resistance with the source, and an electrolytic timer in the circuit.
- 70 12. An electric bomb comprising in combination a shell, an explosive charge, a detonating cap for the charge, including an electric resistance, a source of electricity, a circuit connecting the resistance with the source, normally spaced electrodes in the circuit adapted for co-operation to bridge the space by the electrical deposition of material on one under electrolytic decomposition, a container for the electrodes, and an electrolyte in the container.
- 75 In testimony whereof I have affixed my signature.
